United States Patent Office

Des. 213,780
Patented Apr. 8, 1969

213,780

DENTAL WEDGE

William E. Horn, 4901 Marconi Ave.,
Carmichael, Calif. 95608

Filed May 21, 1968, Ser. No. 12,033

Term of patent 14 years

Int. Cl. D24—03, 04

U.S. Cl. D24—1

FIG. 1

FIG. 2

FIG. 3

FIG. 4

FIG. 5

FIGURE 1 is a top plan view of a dental wedge, showing my new design;

FIGURE 2 is a rear elevational view;

FIGURE 3 is a side elevational view, the opposite side being substantially similar in appearance;

FIGURE 4 is a front elevational view; and,

FIGURE 5 is a bottom plan view.

I claim:

The ornamental design for a dental wedge, as shown and described.
